CIRCUIT INTERRUPTER

Oswald von Mehren, Wilkinsburg, Pa., assignor
to Westinghouse Electric Corporation, East
Pittsburgh, Pa., a corporation of Pennsylvania

Application February 13, 1945, Serial No. 577,637

15 Claims. (Cl. 200—170)

1

This invention relates to circuit interrupters in general, and, more particularly, to arc extinguishing structures therefor. More specifically, the invention relates to improved contact constructions.

It is common practice to provide the contact carrying elements of a circuit breaker with tips made of silver, or of a silver-tungsten or other alloy having better arc-resisting qualities than silver. The use of silver as a contact tip is advantageous due to the instability of the silver oxide produced by the arcing. This silver oxide has about as high a resistivity as copper oxide, but while the latter is very stable at high temperature, the silver oxide instead breaks down under the very same heat of the arc which forms it, and thus restores the conductive capacity of the contact tip. However, silver has the disadvantage that the low melting point of silver has produced many a case of fused or "frozen" contacts—hence the use of a tungsten-silver or other alloy which combines a high melting point with a high resistance to oxidation. These alloys, however, have a fairly high electrical resistivity due to the tungsten or other components. Consequently, contact tips made of such alloys have a relatively low current carrying capacity and, if kept within normal size, are unable to carry temporary current surges which may reach a value several times the normal current flowing through the circuit.

The purpose of my invention is to provide means whereby the current carrying capacity of a circuit breaker using arc-resisting alloy contact tips may be increased, in its closed position, to a point where such current surges as mentioned above may be easily taken care of, this without affecting the arc resisting quality of its circuit breaking elements.

Another object of my invention is to provide an improved circuit interrupter in which abutting cooperable contacts are spanned in the closed-circuit position by one or more bridging contacts. It is a more specific object to adapt such a contact construction to an interrupter of the type establishing both pressure-generating and interrupting arcs, and in which the pressure of fluid generated at the pressure-generating arc is directed toward the interrupting arc to effect the latter's extinction.

Another object is to provide an improved contact construction in which one or more bridging contacts are utilized in the closed-circuit position to span the contacts, and in which improved biasing means are furnished to wedge the bridg-

2

ing contacts against the cooperable contacts in the fully closed-circuit position of the interrupter.

Further objects and advantages will readily become apparent upon a reading of the following specification, taken in conjunction with the accompanying drawings, in which:

Fig. 1 is an elevational view, partly in section, of a circuit interrupter embodying my invention, and shown in the closed-circuit position;

Fig. 2 is an enlarged vertical sectional view through the left-hand arc extinguishing unit of Fig. 1, the contacts being shown in the closed-circuit position;

Fig. 3 is a vertical sectional view through the arc extinguishing unit of Fig. 2, taken at right angles to said view, but the contacts being shown in the fully open-circuit position;

Fig. 4 is a sectional view taken along the line IV—IV of Fig. 2;

Fig. 5 is a sectional view taken along the line V—V of Fig. 2;

Fig. 6 is a fragmentary enlarged view, taken in substantially vertical section, of the upper contact construction shown in Fig. 2, the contacts being shown in the closed-circuit position;

Fig. 7 is a fragmentary enlarged vertical sectional view through the lower contact construction of Fig. 2 modified to show two points of contact of the bridging member, the contacts also being shown in the closed-circuit position; and

Figs. 8 through 27 are detailed views of the contact elements employed in the improved contact constructions of my invention.

Referring to the drawings, and more particularly to Fig. 1 thereof, the reference numeral 1 designates a tank filled to the level 2 with a suitable arc-extinguishing fluid 3, in this instance circuit breaker oil. Depending from the cover 4 of the tank 1 are two insulating bushings 5, 6, through which extend terminal studs (not shown). Threaded to the lower end of the terminal studs, and clamped thereto, are contact feet 7, 8 which rigidly support in place two identical arc-extinguishing units generally designated by the reference numeral 9.

The two units 9 are electrically interconnected in the closed-circuit position as shown in Fig. 1 by a conducting cross-bar 10, which is operated reciprocally in a vertical direction by an insulating operating rod 11 actuated by suitable mechanism (not shown).

Rigidly secured to the outer extremities of the cross-bar 10 are two movable contacts 12, 13,

which contact the intermediate contacts 14 of the interrupters in the closed circuit position thereof, as is more clearly shown in Fig. 2. The intermediate contact 14 in turn engages in abutting relation, a relatively stationary contact 15.

The separation between the relatively stationary contact 15 and the intermediate contact 14 during the opening operation takes place in a pressure-generating chamber, generally designated by the reference numeral 16, and in this instance being formed by side members 17, 18 cooperating with upstanding curved members 19 in a manner more clearly shown in Fig. 4.

Suitable plates properly configured are held in contiguous relation by insulating tie rods 20. The several plates collectively form two vertical flow passages, generally designated by the reference numeral 21, which interconnect the pressure-generating chamber 16 with a plurality, in this instance four, inlet passages 22. Consequently, during the opening operation, fluid, in this instance oil, put under pressure by the pressure-generating arc established between the contacts 14, 15, flows downwardly in the direction as indicated by the arrows in Fig. 2, inwardly through the inlet passages 22 to contact the interrupting arc, whence the fluid passes through orifices 23 provided by insulating orifice plates 24 to exhaust out of the unit 8 through exhaust passages 25, as more clearly shown in Fig. 3.

Certain features of the passages and inlets just described are set forth and broadly claimed in a patent application filed November 11, 1942, Serial No. 465,244, now United States Patent 2,406,469, issued August 27, 1946, by Leon R. Ludwig, Winthrop M. Leeds and Benjamin P. Baker, and assigned to the assignee of the instant application.

The several plates have portions 26 removed therefrom to form a cylindrical cut-out portion in which is inserted an insulating tube 27. Movable within the tube 27 is a tubular member 28 having a flange portion 29 at its lower extremity, the flange portion being conically-shaped as indicated at 30. A compression spring 31 having its upper seat against a plate 32 serves to bias the tubular or cup-shaped member 28 in a downwardly direction.

The conically-shaped portion 30 serves as wedging means to bias a plurality, in this instance three, bridging contacts 33 radially inwardly against the contacts 12, 14 in the closed circuit position, as shown in Fig. 2.

The individual bridging contacts 33 are more clearly shown in Figs. 20 and 21 of the drawings. Also, Figs. 17 and 18 collectively show more clearly the construction of the tubular member 28.

The three bridging contacts 33 are secured in position by a contact holder 34 shown more clearly in Figs. 25 through 27 of the drawings. A pin 35 having a roller 36 thereon extends loosely through apertures 37 provided in a bifurcated portion 38 of the bridging contact 33, as shown more clearly in Fig. 20. The roller 36 mounted on the pin 35 is positioned between the legs of the bifurcated portion 38 and bears against the conical portion 30 of the flange 29 in the closed circuit position as shown in Fig. 2.

A cup-shaped member 39, as shown more clearly in Figs. 23, 24 of the drawings, is threaded into the contact holder 34 by a threaded connection at 40. The intermediate contact 14 has an integrally formed flange portion 41 which engages a shoulder 42 of the cup-shaped member 39 during the closing stroke as shown in Fig. 2. A

compression spring 43 has its lower seat on the flange 41 and has its upper seat against a recess 44 formed in the tubular member 28, as shown more clearly in Fig. 18.

The drawings illustrate the working principle of my invention as applied to an arc-breaking grid as used in a 69 kv. oil circuit breaker. Referring to Fig. 2, which shows the contacts in their closed circuit position, it will be observed that there are provided the regular three main elements of such a grid, namely, the moving contact 12, the intermediate contact 14 and the relatively stationary contact 15 which, through the shunts 45, is electrically connected to the contact foot 7 which is clamped to the current carrying terminal stud of the condenser bushing of the breaker. The contact making ends of the three elements are provided with tungsten-silver or other arc-resisting alloy tips 46, 47, 48 and 49. Considering the intermediate contact 14 first, it is noted that the contact is provided with a shoulder 41 through which it engages a cup 39 which is fastened to the contact holder or spider 34. The latter carries a series of contact bridges 33 so arranged as to form a bridge contact between the intermediate contact 14 and the movable contact 12 beyond the contact tips 48, 49, when in the position shown in Fig. 2. These contact bridges 33 are held in place by pins 35 positioned in suitably located clearance holes 37a in the corresponding faces of the spider 34. Through these clearance holes 37a, the said contact bridges 33 are allowed a limited but sufficient radial motion. These contact bridges 33 are provided with rollers 36, through which they bear on the cone-shaped cup 28, which is biased downwardly by the accelerating spring 31. The other accelerating spring 43 biases the intermediate contact 14 in relation to the coned cup 28 as shown.

In the closed position shown in Figs. 2 and 7, the pressure exerted by the moving contact 12 upon the intermediate contact 14 forces the rollers 36 to bear against the coned cup 28 and raise the latter upwardly against the spring 31. This forces the contact bridges 33 to close around the intermediate contact 14 and the moving contact 12 so as to grip the two together and substantially increase the contact area between points of high conductivity beyond the tungsten silver alloy tips 48, 49.

The contact pressure of these bridges 33 is quite high due to the wedging or biasing action exerted by the cone 28. When the breaker has to be opened, a release of the pressure from the moving contact 12 causes the whole assembly to travel downwardly as one unit under the influence of the compression spring 31 until the lower end of the cone 28 is stopped by the grid plate 50. At this instant, all pressure on the contact bridges 33 ceases, and the latter together with the spider 34 separate themselves from the cone 28 and continue their downward travel until the spider 34 is stopped by the grid plate 51.

This extra travel of the spider 34 is just sufficient to establish a mechanical clearance between the rollers and the cone 28. The intermediate contact 14 continues its downward travel under the action of compression spring 43 until it reaches the position shown in Fig. 3. This position is determined by the shoulder 41 hitting the spider 34. Up until now the moving and the intermediate contacts 12, 14 have remained in contact with each other and it is only at this instant that the separation between the two takes place. Thus, the arcing takes place only between the

tungsten silver alloy contact tips 48, 49, well beyond the position of the contact bridges 33.

In closing the breaker, the moving contact 12 moves upwardly to first engage the intermediate contact 14, whence it moves the latter upwardly against the biasing action exerted by the spring 43 until the shoulder 41 engages the cup 39. When this occurs, the contact plane common to the two contact tips 48, 49 has reached the position shown in Fig. 2, i.e. in the center of the contact bridges 33.

At this point the spider 34 is raised with the contacts 12, 14 and the rollers 36 are brought to bear against the cone 28, and thus the bridges 33 are forced to close around the contacts 12, 14 while the contact pressure of these bridges 33 increases with an increase in the compression of accelerating spring 31. The springs 31 and 43 must be so proportioned that the final load of spring 43 is less than the initial load of the spring 31.

It will be noticed here that the main characteristic of this device lies in the instantaneous release of the pressure on the contact bridges 33, as soon as the cone 28 is stopped in its downward motion, thus leaving the intermediate and moving contacts 12, 14 free to continue together their downward motion until their contact plane is well beyond the position of the bridge contacts 33, so that the actual arcing will take place only between the contact tips 48, 49 provided for this purpose.

In order to provide cooling of the contacts when the breaker is closed, the contact holder or spider 34 is provided with longitudinal passages 52, as more clearly shown in Fig. 27. These passages 52, together with perforations 53, 54 and 55, allow the oil to circulate around the contact 14, and thus the oil becomes a cooling medium.

During the opening operation after the tubular member 28 has struck and is stopped by the plate 50, inward biasing tension is released upon the rollers 36. However, even after the release of such tension the contact bridges 33 are still in engagement with the contacts 12, 14. Two forces now come into play to cause radial outward retraction of the contact bridges 33. One of these forces is the force of gravity which tends to cause rotation of the contact bridges 33 so that the pins 35 thereof will be moved outwardly within the apertures 37a of the contact holder 34. Also the sliding friction exerted by the intermediate contact 14 upon the contact bridges 33 tends to assist the force of gravity in causing rotation of the contact bridges 33 so that the pins 35 are forced outwardly. Consequently, these two forces, namely, the force of gravity and the sliding frictional force of the intermediate contact 14 tend to cause freeing outward retraction of the pins 35 to thereby result in radial outward movement of the contact bridges 33.

It will furthermore be noticed that the lower edges of the contact bridges 33, as viewed in Fig. 21, are rounded. This cooperates with the beveled surface of the arc resisting tip portion 49 of the movable contact 12 to prevent jamming of the contact surfaces during the closing stroke.

The circuit breaking device illustrated in the top section of the grid is in principle a duplication of the one just described. The only changes are those of a structural nature necessitated by the shape of the stationary contact which, in this case, has to be connected through

the shunts 45 to the current carrying foot 7 of the grid.

More specifically, the contact bridges 33 are secured in position in a contact holder or spider 56, shown more clearly in Figs. 14, 15, 16 and 22 of the drawings. It will be observed that the contact holder 56 has a pair of longitudinal slots 57 provided therein through which moves a pin 58. The pin 58 passes through the contact 15 having integrally formed therewith a cross-member 59 of rectangular configuration. The cross-member 59 moves within a pair of slots 60, also provided in the contact holder 56.

The coned member for the upper contact construction is generally designated by the reference numeral 61, and comprises three pieces, respectively designated by the reference numerals 62, 63, and 64. The member 62 has a configuration more clearly shown in Figs. 8 and 9 of the drawings; the member 63 has a configuration more clearly shown in Figs. 10 and 11 of the drawings; and member 64 has a configuration more clearly shown in Figs. 12 and 13 of the drawings.

In assembling, the threaded stop ring 64 is threadedly secured at 65 to the ring 63, the latter being secured by screws (not shown) to the member 62. A compression spring 66 serves the same function as the spring 31 in the lower contact construction, and a compression spring 67 serves the same function as the spring 43 in the lower contact construction. A screw 68 threaded into the contact foot 7 at 69 has its head 70 serve as a stop for downward travel of the coned member 61.

Consequently, during the initial opening travel from the position shown in Fig. 2, the entire unit moves downwardly under the influence of the compression spring 66 until the flange portion 71 of the member 62 strikes the head 70 of the screw 68. This substantially one-eighth inch travel furnishes the requisite contact pressure for the several contact gaps of the interrupter, the compression spring 66 thus furnishing the requisite contact pressure. However, after the shoulder 71 strikes the head 70, downward movement of the member 62 ceases and thereafter the contact bridges 33, spider 56, relatively stationary contact 15 and intermediate contact 14 together move downwardly as a unit under the influence of spring 67 until the spider 56 strikes the stop ring 64, at which time there is sufficient mechanical clearance between the rollers 36 and the cone portion 30 so that the stationary contact 15 thereafter slides downwardly through the contact bridges 33 to a position as shown in Fig. 3.

After the stationary contact 15 has moved to the position shown in Fig. 3, the cross-bar 59 has struck the ring 63, thereby stopping the downward movement of the relatively stationary contact 15. Arcing then takes place between the contact 15 and the intermediate contact 14, but only after the contact 15 has reached the position shown in Fig. 3 where arcing takes place only between the contact tips 46, 47 well out of reach of the bridging contacts 33.

During the closing stroke, the intermediate contact 14 moves upwardly to pick up the stationary contact 15, raising the latter until the pin 58 strikes the top of the slots 57, at which time the contact 15 carries the spider 56 upwardly therewith. However, the upward travel of the spider 56 brings the rollers 36 into engagement with the cone portion 30 of the wedging means 61 so that radial inward pressure is brought to

bear on the bridging contacts 33 to force them radially inwardly against the contacts 14, 15. Further, upward motion compresses the compression spring 66, thereby producing the requisite contact pressure.

From the foregoing description it will be apparent that I have provided an improved contact construction, in which abutting contacts are bridged in the closed circuit position to enable the contacts to carry high momentary current surges without destructive consequences. It will be noted that the bridging contacts are biased radially inwardly to firmly engage the abutting contacts and thereby provide requisite contact pressure between bridging contacts and abutting contacts. It will be noted that the relatively high resistant tungsten-silver alloy tips are bridged in the closed-circuit position, and that during the opening operation arcing takes place at a point beyond reach of the bridging contacts.

Although I have shown and described a specific structure, it is to be clearly understood that the same was merely for the purpose of illustration, and that changes and modifications may readily be made therein by those skilled in the art without departing from the spirit and scope of the appended claims.

I claim as my invention:

1. In a circuit interrupter, a pair of contacts cooperable to establish an arc, and one or more independently laterally movable bridging contacts being wholly laterally movable to span the pair in the closed circuit position with the terminal ends of each bridging contact engaging both the aforesaid contacts.

2. In a circuit interrupter, a pair of cooperable contacts which abut in the closed circuit position, an independently laterally movable bridging contact being wholly movable laterally which spans the pair of contacts in the closed circuit position with the terminal ends of the bridging contact engaging the aforesaid pair of contacts, and biasing means to bias the bridging contact toward the pair of contacts when the latter are in the closed position.

3. In a circuit interrupter, a pair of contacts cooperable to establish an arc, a contact holder, a plurality of bridging contacts, the contact holder pivotally carrying the bridging contacts, and the bridging contacts spanning the pair in the closed circuit position so that the terminal ends of the bridging contacts engage the aforesaid pair of contacts.

4. In a circuit interrupter, a pair of contacts cooperable to establish an arc, a contact holder, a plurality of bridging contacts, the contact holder pivotally carrying the bridging contacts, the bridging contacts spanning the pair in the closed circuit position, and biasing means to bias the bridging contacts toward the pair of contacts in the closed circuit position so that the terminal portions of the bridging contacts are pressed against the aforesaid pair of contacts.

5. In a circuit interrupter, a pair of contacts cooperable to establish an arc, a contact holder, a plurality of bridging contacts, the contact holder pivotally carrying the bridging contacts, the bridging contacts spanning the pair in the closed circuit position, and biasing means to bias the bridging contacts radially inwardly toward the pair of contacts in the closed circuit position so that the terminal portions of the bridging contacts are pressed against the aforesaid pair of contacts.

6. In a circuit interrupter, a pair of contacts cooperable to establish an arc, a contact holder, a plurality of independently laterally movable bridging contacts carried by the contact holder 5 being wholly movable laterally, and wedging means to bias the bridging contacts radially inwardly to span the pair of contacts in the closed circuit position of the interrupter with the terminal ends of each bridging contact engaging both the aforesaid contacts.

7. In a circuit interrupter, a pair of contacts cooperable to establish an arc, a contact holder, a plurality of independently laterally movable bridging contacts carried by the contact holder 15 being wholly movable laterally, and wedging means comprising an annular conically-shaped member to bias the bridging contacts radially inwardly to span the pair of contacts in the closed circuit position of the interrupter with the terminal ends of each bridging contact positively engaging both the aforesaid contacts.

8. In a circuit interrupter, a pair of cooperable contacts which abut in the closed circuit position, a contact holder, a plurality of independently laterally movable bridging contacts, means pivotally mounting the bridging contacts in the contact holder, and a tubular member having a flange portion, the flange portion being conically shaped to wedge the bridging contacts radially inwardly to span the contacts in the closed circuit position of the interrupter so that the terminal portions of the bridging contacts are pressed against the aforesaid pair of contacts.

9. In a circuit interrupter, a pair of cooperable contacts which abut in the closed circuit position, an independently laterally movable bridging contact to span the pair in the closed circuit position, means biasing the bridging contact into bridging relationship in the closed circuit position of the interrupter so that the terminal ends of the bridging contact are pressed against both the aforesaid contacts, and means for releasing the tension of the biasing means prior to separation of the pair of contacts during the opening operation.

10. In a circuit interrupter, a pair of cooperable contacts which abut in the closed circuit position, a bridging contact to span the pair in the closed circuit position, means biasing the bridging contact into bridging relationship in the closed circuit position of the interrupter so that both terminal ends of the bridging contact are pressed against the two aforesaid contacts, means for releasing the tension of the biasing means prior to separation of the pair of contacts during the opening operation, and means permitting one of the contacts to slide past the bridging contact during the opening operation following release of tension of the biasing means so that arc drawal takes place away from the bridging contact.

11. In a circuit interrupter, a pair of contacts one of which is rod-shaped cooperable to establish an arc, one or more bridging contacts adaptable to span the pair of contacts in the closed circuit position with the terminal ends of each bridging contact engaging both the aforesaid contacts, a coil spring surrounding said one contact, camming means to force the one or more bridging contacts into engagement with the pair of contacts, and the coil spring biasing the camming means into operative position in the closed circuit position of the interrupter.

12. In a circuit interrupting device, a rod-shaped contact cooperable with another contact in

abutting relation in the closed circuit position, bridging means adaptable to completely span the contacts in the closed circuit position, a cam to bias the bridging means against the contacts, and a coil spring encircling the rod-shaped contact biasing the cam into operative relationship in the closed circuit position of the interrupter.

13. In a circuit interrupter, a pair of contacts one of which is rod-shaped cooperable to establish an arc, one or more bridging contacts adaptable to span the pair of contacts in the closed circuit position with the terminal ends of each bridging contact engaging both the aforesaid contacts, a coil spring surrounding said one contact, camming means to force the one or more bridging contacts into engagement with the pair of contacts, the coil spring biasing the camming means into operative position in the closed circuit position of the interrupter, and means for causing opening separating motion of the contacts to cause arc drawal at a place away from the one or more bridging contacts.

14. In a circuit interrupting device, a rod-shaped contact cooperable with another contact in abutting relation in the closed circuit position, bridging means adaptable to completely span the contacts in the closed circuit position, a cam to bias the bridging means against the contacts, a coil spring encircling the rod-shaped contact biasing the cam into operative relationship in the closed circuit position of the interrupter, and means for causing opening separating motion of

the contacts to cause arc drawal at a place remote from the bridging means.

15. A circuit interrupter including a pair of contacts cooperable to establish an arc, one or more independently laterally movable bridging contacts being wholly laterally movable to span the pair in the closed circuit position with the terminal ends of each bridging contact engaging both the aforesaid contacts, and means causing the first said pair of contacts to remain in engagement and slide past the one or more bridging contacts during the opening operation and thereafter separate from each other so that arc drawal takes place away from the one or more bridging contacts.
